To all whom it may concern:

Be it known that I, George H. Kress, a citizen of the United States of America and resident of Johnson City, Broome County, New York, have invented a new, original, and ornamental Design for a Typewriter, of which the following is a specification, reference being had to the accompanying drawing, forming part thereof.

The figure is a perspective view of the typewriter as viewed from the left and in front of the keyboard.

The side of the typewriter opposite to the one

shown in the drawing is the same as the side shown, while the back of the machine is plain or conventional.

The dominant features of the design reside in the portion of the machine shown in solid lines in the drawing. A conventional keyboard is shown in dotted lines.

I claim:

The ornamental design for a typewriter, substantially as shown and described.

GEORGE H. KRESS.
